UNITED STATES PATENT OFFICE.

THOMAS J. ST. LOUIS, OF WEST SUPERIOR, WISCONSIN.

LOG-HAULER.

SPECIFICATION forming part of Letters Patent No. 600,749, dated March 15, 1898.

Application filed September 18, 1897. Serial No. 652,139. (No model.)

To all whom it may concern:

Be it known that I, THOMAS J. ST. LOUIS, of West Superior, in the county of Douglas and State of Wisconsin, have invented a new and Improved Log-Hauler, of which the following is a full, clear, and exact description.

My invention relates to an improvement in log-hauling devices intended for use in connection with sleds; and it consists of certain novel features, which will be hereinafter described and claimed.

Reference is to be had to the accompanying drawings, forming a part of this specification, in which similar characters of reference indicate corresponding parts in all the views.

Figure 1 is a top plan view of the log-hauling device. Fig. 2 is a side elevation of the same. Fig. 3 is a bottom plan view, and Fig. 4 is a plan showing the chain and the stakes by which it is kept in place upon curves.

In the northern lumbering districts logs are principally removed from the woods to the rivers or railroads by means of sleds in the winter-time and when there is snow on the ground. This has heretofore been done by using horses as a motive power. The object of my device is to substitute steam-power for the horses.

In order to provide means by which the log-hauling device may exert its power without tearing up the roadway or without using rails, I use the stationary chain C, which is stretched from one end of the roadway to the other and is fastened at each end. This chain is engaged by a chain hauling or winding mechanism mounted upon a suitable frame A, which frame is supported upon runners a by means of cross-beams or bolsters A² and central pins or king-bolts a'. This permits the sled or bob under each end of the frame to pivot, as may be necessary, in going about curves and also to rock when passing over small rises or obstructions.

Upon the framework A is mounted a boiler G and a motor which consists, as shown in the drawings, of double engines B, connected with a common shaft B'. Upon the shaft B' are mounted gears b and b³, which are of different sizes and are adapted to engage, respectively, with the gears b' and b², mounted upon the shaft of the chain-winding mechanism. As will be noticed in Fig. 1, one set only of these

gears is in operation at a time. The gears b and b³ are movable lengthwise upon their shaft, so that either may be shifted from engagement with its gear and the other be placed in engagement with its gear, thus providing for a change in speed.

The chain-winding mechanism shown in the drawings consists of a sprocket-wheel B² of the kind which is adapted to engage with an ordinary chain. This sprocket-wheel is loose upon its shaft and is engaged for rotation by means of a clutch B³, which is mounted upon the same shaft and is movable into or out of engagement by means of the hand-lever B⁵. The chain C is first passed around the idlers or guiding-wheels I, which are mounted below the sprocket-wheel B² and upon each side thereof, the lower side of these wheels being close to the ground, so that the pull upon the chain is from a low point upon the hauling device, and the chain is therefore at all times held low enough to be engaged by the pins C' (shown in Fig. 4) and by which the chain is held in position upon curves and prevented from pulling toward the inner edge of the curve.

I have provided in addition to the above-described mechanism a separate rope-winding mechanism consisting of a drum B⁴, mounted upon the frame and connected to the engine-shaft B' by means of the gear and pinion b⁵ and b⁴. This rope-winding mechanism may be operated independently of the chain-winding mechanism by freeing the clutch B³. It may then be used for pulling logs into the roadway or for any other purpose desired. A cable wound upon the drum B⁴ may be led through guide-pulleys in any direction and used for any purpose desired. While engaged in this work it is of course understood that the device is anchored by attachment in any suitable or convenient manner to fixed objects, such as stumps or trees.

The rut-cutter consists of the two bars D, which are pivoted at d to the frame A. These bars are crossed and fastened together in the shape of the letter X, the pivot being at the point of crossing. The lower outer edges of these bars are provided with shoes D', consisting of steel plates which project a slight distance below the ends of the bars D. These shoes are in line with the runners a and are

placed between the same. The upper ends of the bars D engage uprights or stops D', fixed to the frame A and limiting the amount of swing of the bars. This amount of swing 5 is sufficient to permit one of the shoes D' to drop slightly below the level of the runners, so as to cut a rut a little deeper than it was when the runner ran over it. By this means 10 a rut may be formed of any depth desired, the result being that the sleds, which are clamped to the log-hauling device and which follow thereafter, will be guided and held in these ruts. In consequence of this all the sleds will 15 follow in the same track, and this track may be iced, so that the friction of hauling a load will be small.

I have provided means for icing the track, consisting of tanks E, mounted upon the frame A and each provided with a discharge- 20 pipe e, adapted to discharge the water into the ruts. This water will ordinarily freeze at once and thus provide an icy track for the sleds to slide over.

The sleds upon which the logs are to be 25 loaded may be of any suitable or usual form and are connected to the rear end of the log-hauling device or engine by means of the chain F' or the connecting-bar F, or, when desired, by using both. A number of sleds may thus 30 be connected behind the frame A.

The hauling capacity of the device is limited only by the power of the engines mounted thereon and of the chain C.

The use of a steam-operated device of this 35 character will save in the cost of logging in many ways. In the first place the supplies necessary for the device, which will have to be hauled into the camps, will consist only of oil and such other little supplies as are necessary 40 in the operation of the ordinary steam-engine. The fuel for operating the engine may be obtained in the woods and with practically no cost. When using horses or oxen for this purpose, feed has to be purchased 45 and hauled into the camps, which is an item of considerable expense. At the same time the use of horses or oxen necessitates drivers to attend to them, the expense of which will amount to as much as the expense of the men 50 who operate the engine. Moreover, when the

engine is not in use this expense stops, while the teams eat whether they are at work or not.

To one end of the framework of my device I attach a snow-plow H, which is of the usual V shape. If desired, a snow-plow may be attached to each end of the device. 55

A steering device may be applied to the sled, if desired; but this is not considered necessary, as the sled cannot well do otherwise than follow the chain, which is itself held in 60 the roadway, as described.

Having thus described my invention, I claim as new and desire to secure by Letters Patent—

1. A log-hauling device, comprising a frame 65 mounted upon sled-runners and provided with a locomotive apparatus, rut-cutters mounted upon said frame, consisting of two connected crossed bars pivoted at their point of crossing and having plows on their lower 70 ends, and stops upon the frame adapted to engage the upper ends of said bars to permit one of the plows to drop below the sled-runners, substantially as described.

2. A log-hauling device, comprising a frame 75 mounted upon sled-runners and provided with a locomotive apparatus, rut-cutters mounted upon said frame consisting of two connected crossed bars pivoted at their crossing and having plows on their lower ends, 80 stops upon the frame adapted to engage the upper ends of said bars to permit one of the plows to drop below the sled-runners, and water-tanks arranged to discharge in the ruts, substantially as described. 85

3. A log-hauling device, comprising a frame mounted on sled-runners, a chain-winding mechanism mounted thereon, a chain extending along the road and fastened at each end, 90 said chain being engaged by the chain-winding mechanism, a rut-cutter consisting of pivoted bars having a shoe or plow upon their lower ends adapted to drop below and in line with the runners, a limiting-stop therefor, and a snow-plow attached to the end of the frame, 95 substantially as described.
